UNITED STATES PATENT OFFICE.

FRED C. SEIDEL, OF TOLEDO, OHIO, ASSIGNOR TO THE TOLEDO MACHINE & TOOL COMPANY, OF TOLEDO, OHIO, A CORPORATION OF OHIO.

KNOCK-OUT MEANS FOR PRESSES.

Application filed June 8, 1927. Serial No. 197,377.

This invention relates to presses, but more particularly to ejector mechanism for presses for ejecting the article from the die upon completion of the work.

5 Most presses employ an ejector bar having a depending pin or stem which extends into the movable die and when the slide carrying the movable die is being raised, the ejector bar engages an adjustable screw on a stationary abutment bar which causes ejection of the work from the die.

It frequently becomes necessary to adjust the position of the slide relatively to the bed or stationary die, and for this purpose the 15 pitman joining the slide and crank is made adjustable, the adjusting parts being positioned adjacent the connection between the pitman and slide.

Heretofore, in order to effect this adjustment, it has usually been necessary to remove 20 the abutment bar when the slide is in its lower position to afford access to the length-adjusting means of the connecting rod. This is decidedly impractical and inefficient, because the abutment bar is a heavy cumbersome piece, weighing in the case of large 25 presses, over a hundred pounds, and requires the services of several men as well as taking a considerable amount of time.

30 Objects of this invention are to overcome the above difficulties; to provide an abutment bar which can be quickly and easily moved out of the way to afford access to the adjusting parts; and to provide in a press the 35 new and improved features of construction hereinafter described.

The invention is shown by way of illustration in the accompanying drawings, in which:

40 Fig. 1 is a front elevation of the slide and associated parts; Fig. 2 is a vertical sectional elevation on the line 2-2 of Fig. 1; Fig. 3 is a transverse section on the line 3-3 of Fig. 1; and, Fig. 4 is a fragmentary view 45 on an enlarged scale of the mounting for one end of the abutment bar.

The illustrated embodiment of the invention comprises a press having a frame provided with uprights 1 and a bed 2 to receive 50 the usual stationary die. Formed on opposite sides of the uprights 1 are guide plates or gibbs 3, in which a slide or plunger 4 is vertically reciprocable. The slide 4 carries the upper movable die (not shown) as will 55 be readily understood.

The slide 4 is operated from a crank (not shown), to which it is connected by means of a pitman or connecting rod 5. The connecting rod 5 is preferably in two parts, 5^a and 5^b which are in screw threaded engagement, 60 a collar 6 encircling the part 5^a for holding the parts in adjusted position. A desirable connection between the parts of the pitman 5 is shown in the patent to Adolph Seidel, Number 1,606,814, issued November 16th, 65 1926, but as this forms no part of the present invention, detail description is not considered necessary.

The lower end of the part 5^b of the connecting rod has suitable connection, in the 70 present instance, ball and socket, with the upper end portion of the slide 5 and may be squared at 7 to receive a wrench or other suitable tool to effect the desired longitudinal adjustment.

75 Formed in the slide 4 is a vertically elongate slot 8 to receive an ejector bar 9 which has limited movement in the slot. Pins 10 project laterally from opposite sides of the bar 9 and serve to hold the bar in place 80. Depending from the central portion of the bar 9 is a pin 11, which is adapted to extend into the movable die for engaging and ejecting the article after the work is completed.

When the slide 4 is raised the ejector bar 85 9 engages adjustable abutment screws 12 carried by transverse abutment bars 13 and 14, respectively and in this manner the work is forced away from the movable die. It will be understood by those skilled in this art 90 that the sheet of metal upon which work has been performed often sticks or adheres to the movable die, and some means must be provided for ejecting the work after the movable die has been separated from the stationary die. The bar 14 is preferably fixed at its opposite ends to the frame and is bowed 95 outwardly as shown.

Projecting laterally from each guide plate 3 is a pair of vertically spaced brackets 15, 100 and each end of the abutment bar 13 is placed between a pair of such brackets. In each set of brackets 15 are registering openings 16, and formed in each end of the bar 13 is an opening 17 which registers with the 105 bracket openings 16. Extending through the registering openings 16 and 17 are pins 18 having knurled heads 19, and in this manner the bar is securely held in place.

When it is desired to adjust the length of 110

the connecting rod 5 with the slide in its lowered position, one of the pins 18 is removed. This leaves one end of the bar 13 pivotally connected to the frame and the other end 5 free to be swung outwardly to enable access to be readily afforded to the squared portion 7. Proper length adjustment of the connecting rod can thereafter be quickly made.

It will be understood that in accordance 10 with my invention the time required for effecting the length adjustment of the connecting rod is reduced to a minimum, and instead of requiring the services of several men to handle the heavy cumbersome abutment bar, a single man can do the work in an efficient manner. Although it has been necessary heretofore, in making the adjustment referred to, to remove entirely the abutment bar from the frame, by my im- 15 proved construction such removal is rendered unnecessary.

While I have shown my invention in one embodiment, it is to be understood that numerous changes in details of construction 20 and arrangement may be effected without departing from the spirit of the invention, especially as defined in the appended claims.

What I claim as new and desire to secure by Letters Patent is:

30 1. In a press, the combination of a frame, a slide reciprocable in said frame, a connecting rod for said slide having length-adjusting means adjacent said slide, an ejector carried by said slide for ejecting movement relatively thereto, a transverse bar providing an abutment for said ejector and so arranged as to obstruct access to the length-adjusting means when the slide is in lowered position, and a connection between said bar 35 and frame to permit the bar to be swung 40

relatively to the frame for allowing ready access to said length-adjusting means when the slide is in its lowered position.

2. In a press, the combination of a frame, 45 a slide reciprocable in said frame, a connecting rod for said slide having length-adjusting means adjacent said slide, an ejecting element carried by said slide for ejecting movement relatively thereto, brackets projecting from each side of said frame, 50 an abutment element having a bar with its ends between said brackets and providing an abutment for said ejecting element, and pins extending through said brackets and opposite ends of said abutment bar whereby one 55 pin or the other may be removed to permit one or the other end of said bar to be swung outwardly from said frame to afford access to said length-adjusting means when the slide is in its lowered position. 60

3. In a press, the combination of a frame, 65 a slide reciprocable in said frame, a connecting rod for said slide having length-adjusting means adjacent said slide, an ejecting element carried by said slide for ejecting movement relatively thereto, an abutment element for said ejecting element, and connection between said abutment element and said frame including a hinge joint between 70 one end of said element and frame and a detachable joint between the other end of said element and frame, whereby said abutment element may be detached and swung outwardly from the frame when in lowered position to afford ready access to said length- 75 adjusting means.

In testimony whereof I have hereunto signed my name to this specification.

FRED C. SEIDEL.
